ELECTRIC SWITCH

Russell S. Davis and Elwood T. Platz, Detroit, Mich., assignors to BullDog Electric Products Co., Detroit, Mich., a corporation of West Virginia

Application July 1, 1952, Serial No. 20,441

Term of patent 14 years

(Cl. D26—13)

Fig. 1 is a front elevational view of an electric switch showing our new design.

Fig. 2 is a side elevational view.

Fig. 3 is a bottom elevational view.

The characteristic features of our design of the electric switch disclosed reside in the embossed cover plate and handle on the front having the configuration shown.

We claim:

The ornamental design for an electric switch, substantially as shown and described.
